UNITED STATES PATENT OFFICE.

VICTOR FEGLEY, OF PHILADELPHIA, PENNSYLVANIA, ASSIGNOR TO FABEC MANUFACTURING COMPANY, OF CAMDEN, NEW JERSEY, A CORPORATION OF NEW JERSEY.

INKING MECHANISM FOR PRINTING-PRESSES.

1,246,574.

Specification of Letters Patent.

Patented Nov. 13, 1917.

Application filed March 19, 1914. Serial No. 825,908.

To all whom it may concern:

Be it known that I, VICTOR FEGLEY, a citizen of the United States, residing in Philadelphia, Pennsylvania, have invented certain Improvements in Inking Mechanism for

Printing-Presses, of which the following is a specification.

One object of my invention is to provide means for automatically supplying ink to the ink distributing disk or platen of a printing press, so that a given amount of ink will be supplied to the disk to make a proper impression.

A further object of the invention is to provide means for regulating the amount of ink supplied to the press.

A still further object of the invention is to provide an ink tube which can be readily attached to the press and to the mechanism for feeding the ink from the tube.

These objects I attain in the following manner, reference being had to the accompanying drawings, in which:—

Figure 1, is a side view in dotted lines illustrating a common form of job press and showing my improved ink supplying mechanism in full lines;

Fig. 2, is a view looking in the direction of the arrow, Fig. 1;

Fig. 3, is an enlarged side view of the ink supplying mechanism;

Fig. 4, is a plan view of the mechanism shown in Fig. 3;

Fig. 5, is an end view;

Fig. 6, is an enlarged sectional view, showing the feed mechanism;

Fig. 7, is a detached perspective view of the ink tube;

Fig. 8, is a perspective view of the lever for actuating the feeding mechanism;

Fig. 9, is a transverse sectional view on the line *a—a*, Fig. 3;

Fig. 10, is a view with the notched supports removed and an enlarged tube resting directly on the main support; and

Fig. 11, is a sectional view of the ink tube filled and in the form in which it is sold.

Referring to Fig. 1, 1 is the frame of a printing press. 2 is the main shaft. 3 is the bed of the press to which the type form is attached. 4 is the platen. 5 is the ink distributing disk. 6 and 7 are the ink distributing rollers carried by the frame 8, the lower portion 9 of which is shown in full lines. The frame is pivoted at 10 and

the rollers 6 and 7 travel over the inking disk and over the type of the frame, which is held to the bed. The above is a description of an ordinary type of job printing press.

Secured to a fixed portion 11 of the press is the supporting arm 12, held thereto by a bolt 13. This arm carries the frame 14; being secured thereto by a bolt 14^a. The bolt is adapted to a slot in the arm 12 so that the

frame can be adjusted thereon. Secured to the frame 14 is the main support 15 on which is mounted a notched support 16 shaped to receive the ink tube 17, shown clearly in

Fig. 6. The notched support is shaped to fit the tube, as illustrated in Fig. 8, and is held in place by projections 18 in the form of screws, which are located in recesses at the sides of the notched support. By making the notched support interchangeable any

size tube may be used. The largest size ink tubes may be located directly on the support 15, as in Fig. 10; being held in place by the projections 18. Other supporting means for the tube will readily suggest themselves.

A clamp plate 19 extends over the top of the tube 17, and, in the present instance, is firmly held to the main support by two screws 20. Other means of clamping may be used without departing from the essential

features of the invention.

The ink tube 17 is made as shown in Figs. 6 and 7, and has at one end a fixed closure 21, in the present instance of cork, and this closure has a small groove or grooves 22 at

its upper end, providing an outlet for the ink. The tube is beveled at 23 on a line with the face of the ink distributing disk 5 so that, when the rollers 6 and 7 pass over the disk and over the end of the tube 17, they take up the ink that is forced out of the tube by a plunger 24.

This plunger 24 is made of cork or other suitable material and is the closure for the rear end of the tube, when said tube is filled or purchased.

Back of this plunger is a disk 25, which is screwed onto the stem of a block 26 and secured to the block by screws 27 is a ring

28. Mounted in the ring is a head 29 of a feed screw 30. The end of the head is pointed and bears against the center of the block. The head is slightly rounded, as shown, so that should the tube be out of line with the feed screw it will properly feed ink

in the tube. When the feed screw is with-

drawn, by releasing the half nut 34 the head 29 comes in contact with the overhanging screws 27 and the disk 25 is withdrawn clear of the end of the tube 17, after which the 5 clamps can be removed and the empty tube withdrawn and a filled tube substituted for it.

Means are provided for feeding the plunger slowly forward as the parts operate, so 10 that a given amount of ink is continuously supplied to the ink distributing disk and, consequently, the type form will be supplied with a proper amount of ink to make the impression.

15 The feed screw 30 has a thread extending throughout its full length and has a longitudinal key-way 31 therein. The feed screw extends through a bearing 33 having a half nut 34 held in place by a thumb bolt 35.

20 The lower portion of the opening in the bearing is smooth while the opening in the half nut 34 is threaded to engage the thread of the feed screw 30 so that, when the feed screw is turned, it will be moved forward, 25 but, when the half nut is released and turned back, the feed screw can be moved longitudinally in either direction, as desired.

30 36 is a hub mounted on the feed screw and this hub has a key 37 which enters the key-way 31 in the screw 30, so that while the screw can be moved longitudinally in the hub it must turn therewith. The hub is held to the main support 15 by a broad headed screw 38 which overlaps the flange 35 39 of the hub, as shown in Fig. 5.

40 36 is a ratchet wheel secured to the hub 36, and this ratchet wheel has a series of fine teeth on its periphery, and mounted loosely on the hub is an arm 41 having a 40 pawl 42 which is forced against the ratchet teeth by a spring 43. The form of the teeth and the pawl is such that the pawl will feed the ratchet wheel in the direction of the arrow, Fig. 5, when the arm is turned in 45 that direction, but when the arm is reversed it will turn without the wheel, as a spring detent pawl 44 on a fixed arm 45 projecting from the main support 15 will hold the wheel from turning backward.

50 In order to actuate the pawl arm from the mechanism of the press, so that it will automatically feed the ink from the tube, the arm has a projecting pin 32 which enters a forked projection of the lever 46, mounted on a pivot pin 47 secured to the main frame 14 of the machine. A spring 48 is mounted on the pivot pin 47. One end of the spring bears against the frame and the other end bears against the lever 46, tending 55 to force the lever against the arm 49 of a lever 50 pivoted at 51 to the frame. This lever is actuated in any manner from the mechanism of the press. In the present instance, it is connected by a link 52 to a lever 60 65 53 pivoted at 53^a on the frame 14, and the

lever 53 is in turn engaged by a lever 54 which passes freely through an opening in a fulcrum plate 55 projecting from the frame 1. In the present instance, the support of this fulcrum plate is a continuation of the arm 70 12, as indicated at 12^a, and the lower end of the lever 54 bears against the portion 9 of the pivoted roller carrying frame 8 so that, as this frame 8 is turned on its pivot to traverse the rollers over the ink distributing disk and the type, it moves away from the arm 54 and, as it returns to the position illustrated in Fig. 1, it strikes the arm, causing it to actuate the pawl and to turn the ratchet wheel 40, and, consequently, to 80 move the plunger 24 forward in the tube 17 so as to project a given quantity of ink from the end of the tube into the path of the distributing rollers. This operating means may be modified without departing 85 from the essential features of the invention.

90 The tube 17 has a notch 56 at the rear and a plate 57 enters the notch, so as to prevent the tube from turning, insuring the beveled portion 23 being in the proper position with respect to the ink distributing disk 5. The clamp 19, however, holds the tube rigidly in position.

95 When it is desired to stop the feed of the ink while the press is in motion, I provide a rod 58 having a head 59 which passes through an opening 60 in the frame 14 and through a bearing 61. The end 62 of the rod, when it is moved to its full extent in the direction of the arrow, is in the path of 100 the arm 50 and prevents the movement of the arm and, consequently, the movement of the pawl carrying arm 41. The rod 58 has a notch, as shown in Fig. 3, forming a shoulder 63 which, when it passes through the opening 60 in the frame 41, engages the upper wall of the opening due to the spring 64 which bears upon the underside of the rod and forces it up, thus holding the rod in 105 its projected position, but, as soon as the rod 58 is forced down and pulled back, the mechanism will be allowed to feed ink again from the tube.

110 In order to regulate the movement of the lever 46, which controls the pawl carrying arm, I provide a block 65, the round end of which forms a stop for the lever 46 as it moves back after feeding the wheel forward. The arm has an eccentrically curved surface 66 and the block can be moved forward by a screw which passes through a threaded opening in a portion 68 of the frame. There is a thumb-hold 69 on the end of the rod 67 by which it is turned so that by adjusting the block to any position with 115 respect to the curved surface 66, the movement of the arm 46 can be regulated, consequently, the amount of ink discharged from the end of the tube is controlled.

120 In order to accurately adjust the end 23 125

of the tube to the ink distributing disk 5, I form an extension 70, which projects downwardly from the frame 14 and has a set screw 71 at its lower end which bears upon a portion of the frame of the press. This set screw is held in its adjusted position by a jam nut, as shown in Fig. 1. By turning the screw the end 23 of the tube can be raised or lowered, so as to be brought into proper alignment with the ink distributing disk.

As illustrated in Fig. 2, the tube is preferably located at one side of the center of the press, so that the ends of the distributing rollers will receive the ink and will distribute it onto the disk near its periphery; thus an even distribution of the ink thereon is assured, and, as the rollers take up the ink and distribute it onto the type form each portion of the form will be provided with the proper quantity of ink and, as the feeding mechanism continuously supplies a given quantity of ink, each impression will be supplied with the same amount of ink.

By locating the operating lever 54, for my improved mechanism, in position to be actuated by the frame 8 carrying the rollers, it is automatically thrown out of action when the impression lever is moved to move the bed and inking mechanism of the press from the normal position to prevent the paper contacting with the type, consequently all unnecessary inking of the rollers is avoided and the mechanism is only in operation when the impression is being made.

I claim:—

1. A tube for supplying ink to printing presses consisting of a casing of an even diameter throughout and having one end beveled; a plug forming a closure for the beveled end of the tube and also beveled, said plug having a groove therein at the beveled portion communicating with the interior of the casing so as to allow for the escape of ink from the tube; a plunger tightly fitting the tube and forming a closure for the opposite end thereof and arranged to be moved forward in the tube so as to discharge a given quantity of ink through the groove in the plug.

2. The combination in means for supplying ink to printing presses, of an ink distributor; a tube containing ink and having an opening through which the ink escapes, said opening being so located that the ink distributor will receive ink from the tube as it escapes through the opening; means for supporting the tube; a plunger; a feed screw having a longitudinal slot therein for feeding the plunger forward; a bearing having a threaded portion engaging the feed

screw; a hub having a key therein entering the longitudinal slot in the feed screw; a ratchet wheel secured to the hub; an arm loose on the hub; a spring pawl carried by the arm; and means for actuating the arm on the movement of the press.

3. The combination in means for supplying ink to printing presses, of an ink distributor; a tube containing ink and having an opening through which the ink escapes, said opening being so located that the ink distributor will receive ink from the tube as it escapes through the opening; means for supporting the tube; a plunger; a feed screw having a longitudinal slot therein for feeding the plunger forward; a bearing having a threaded portion engaging the feed screw; a hub having a key therein entering the longitudinal slot in the feed screw; a ratchet wheel secured to the hub; an arm loose on the hub; a spring pawl carried by the arm; a pivoted lever engaging the pawl carrying arm; means for limiting the movement of the lever; and lever mechanism engaging the pawl actuating lever, said lever mechanism being actuated on the movement of the press.

4. The combination in means for supplying ink to printing presses, of an ink distributor; a tube; means for securing the tube in position, said tube having an opening at one end; a plunger in the opposite end of the tube; a feed screw having a block with a screw threaded stem; a disk fitting the tube and mounted on the stem; and means for actuating the screw to feed the plunger forward, the disk being detachable so that, when tubes of different sizes are placed in position, the disk can be removed and another disk substituted therefor.

5. The combination in means for supplying ink to printing presses, of an ink distributor; a tube containing ink having an opening at one end; a plunger at the opposite end of the tube; a disk fitting the tube back of the plunger; a block having a screw threaded stem engaging the disk; a feed screw; and means for actuating the feed screw, said feed screw having a head at its outer end and being loosely mounted in the block, said head having overhanging portions preventing the withdrawal of the head from the recess in the block, the block having a free movement on the head.

In testimony whereof, I have signed my name to this specification, in the presence of two subscribing witnesses.

VICTOR FEGLEY.
